United States Patent

Des. 240,388
Patented July 6, 1976

240,388

DRINKING GLASS

John M. Werling, 209 E. 36th St., Apartment #3,
Kansas City, Mo. 64111

Filed Sept. 18, 1974, Ser. No. 506,959

Term of patent 14 years

Int. Cl. D7—01

U.S. Cl. D7—15

Fig. 1.

Fig. 2.

Fig. 3.

Fig. 4.

FIG. 1 is a front elevational view of a drinking glass embodying my design, all of the glass being undecorated except as shown.

FIG. 2 is a top plan view thereof.

FIG. 3 is a bottom plan view thereof.

FIG. 4 is a vertical section thereof taken on line 4—4 of FIG. 2.

I claim:

The ornamental design for a drinking glass, as shown and described.
